ATTORNEY

UNITED STATES PATENT OFFICE.

JOSEPH LEON GOBEILLE, OF CLEVELAND, OHIO, ASSIGNOR TO THE
SYRACUSE STOVE WORKS, OF SYRACUSE, NEW YORK.

DESIGN FOR A STOVE.

SPECIFICATION forming part of Design No. 23,737, dated October 23, 1894.

Application filed August 20, 1894. Serial No. 520,845. Term of patent 7 years.

To all whom it may concern:

Be it known that I, JOSEPH LEON GOBEILLE, a citizen of the United States, residing at Cleveland, in the county of Cuyahoga and State of Ohio, have invented and produced a new and original Design for Stoves, of which the following is a specification, reference being had to the accompanying drawing, showing a part thereof.

10 The single figure of the drawing serves to fully illustrate the design, which is comprised, chiefly, in the appearance of the front of the stove or range. This front, however, is only possible in a stove of the peculiar 15 style or formation here shown, so that the style of the stove determines the character of the design. Thus, the stove shows a fire box or pot at its middle transversely, and at the front of this and part of the design is the 20 slightly ornamented door —a—, with rows of draft openings —b— and —c— above and below, respectively. On either side of this central door —a— are large doors —d— having the appearance of oven doors, and both 25 are of the same size and design throughout and each has scroll work in quite large fig-

ures across its top and bottom, and a central piece —e— in relief containing an ornamental figure in its own center.

Along the bottom of the stove are three 30 other doors —f—, —g— and —h—, corresponding in arrangement to the larger doors above and having large figured ornamentation peculiar to themselves as part of the design, the style of ornamentation on the two 35 side doors being alike, and the central door having somewhat different ornamentation from these but harmonizing with them.

An interlaced border —j— extends from top to bottom of the front corners of the 40 stove, and a scalloped projecting edge —k— forms an attractive skirting along the lower edge of the stove.

Having thus described my invention, what I claim, and desire to secure by Letters Patent, is—

The design for a stove substantially as herein shown and described.

JOSEPH LEON GOBEILLE.
